(57) **CLAIM**

The ornamental design for a louver assembly, as shown and described.

DESCRIPTION

FIG. 1 is a top perspective view of a louver assembly, showing my new design in an assembled position;

FIG. 2 is a top perspective exploded view thereof, in a disassembled position;

FIG. 3 is a bottom perspective view thereof, in an assembled position;

FIG. 4 is a left elevational view thereof, in an assembled position;

FIG. 5 is a right elevational view thereof, in an assembled position;

FIG. 6 is a top plan view thereof, in an assembled position;

FIG. 7 is a bottom plan view thereof, in an assembled position;

FIG. 8 is a front elevational view thereof, in an assembled position; and,

FIG. 9 is a rear elevational view thereof, in an assembled position.
